(57) **CLAIM**

The ornamental design for windshield wiper as shown and described.

DESCRIPTION

FIG. 1 is a left side, top, and front isometric view of the windshield wiper according to my new design;

FIG. 2 is a right side, bottom, and front isometric view thereof;

FIG. 3 is a front elevation thereof;

FIG. 4 is a rear elevation thereof;

FIG. 5 is a left elevation thereof;

FIG. 6 is a right elevation thereof;

FIG. 7 is a top plan thereof; and,

FIG. 8 is a bottom plan thereof.

The broken lines of FIGS. 1 and 5-8 illustrate portions of the windshield wiper that form no part of the claimed design.
